CLAIM

The ornamental design for a bottle with petaloid base, as shown and described.

DESCRIPTION

FIG. 1 is a perspective view of a bottle with petaloid base showing my new design;

FIG. 2 is a top plan view thereof;

FIG. 3 is a bottom plan view thereof; and,

FIG. 4 is a front side view thereof, the opposite rear and side views are the same.

The broken lines are for illustrative purposes only and form no part of the claimed design.
